ATTORNEY:

UNITED STATES PATENT OFFICE.

ALBERT D. TRENO, OF GLOUCESTER, MASSACHUSETTS, ASSIGNOR TO JOHN HAYS HAMMOND, JR., OF GLOUCESTER, MASSACHUSETTS.

SEPARABLE CASING FOR MUSICAL INSTRUMENTS.

Application filed November 30, 1925, Serial No. 72,130. Renewed March 22, 1929.

This invention relates to improvements in musical instruments and more particularly to improved means for controlling the emission of sound.

5 Broadly stated, it is one object of the present invention to provide an improved casing for a musical instrument of the pianoforte type including means for effectively preventing passage of sound through the walls of 10 the piano, and thus reducing undesired leakage of musical sound.

The invention also relates to the provision of an improved casing which may readily be removed, when desired, from the musical instrument for which it is adapted.

Other objects will appear from the following description taken in connection with the accompanying drawings in which

Figure 1 is a top plan view of so much 20 of a piano and casing therefor as is necessary to an understanding of the invention.

Figure 2 is a front elevation partly in section of the structure of Figure 1.

Figure 3 is a sectional view of one portion 25 of the mechanism shown in Figure 2, taken on the line 3—3 of Figure 2.

Figure 4 is a cross section taken on the line 4—4 of Figure 1 and

Figure 5 is a transverse cross section showing 30 details of the structure of Figure 1.

Like reference characters refer to like parts in the several figures of the drawings.

In the following description and claims, 35 parts will be identified by specific names for convenience of expression, but they are intended to be as generic in their application to similar parts or equivalent construction as the art will permit.

Referring to the drawings and particularly 40 to Figures 1 and 2, there is shown a grand piano, including a fixed casing 10, having therein for the purpose of producing sound, a plurality of tuned strings such as 11, tuned to the notes of the musical scale. It will 45 be understood that there may be provided for each note of the musical scale one or more of such strings as may be required to produce the intensity of sound desired. The strings 11 are mounted in the usual frame 50 12 in a conventional manner. For vibrating the strings of each of the notes of the musical scale by percussion there is provided a suitable hammer action as at 13, each operatively connected to one of the keys 14 respectively, of the manual of the piano. Be-

low the manual and in convenient position for the performer, there is provided a pedal block 16 upon which there is positioned a plurality of pedals shown three in number as at 17, 18 and 19. The two right hand 60 pedals as seen in Figure 2 are connected to the sostenuto and loud pedal actions of the piano in a conventional manner, and having no bearing on the present invention it is thought they need not be further described. 65

The left hand pedal 17 is pivotally mounted in the block 16 and at its rear end is pivotally connected to a vertical reciprocating rod 20, mounted in suitable bearings. The upper end of the rod 20 engages one 70 arm of a pivoted bell crank lever 26, pivoted as at 27 to a fixed portion of the piano. A spring such as a leaf spring 28 is mounted on the casing of the piano and is arranged so that it normally maintains the bell crank 75 lever and associated parts in the position illustrated in Figure 2 and restores the parts to the position shown after displacement. The arrangement is such that when the front end of the pedal 17 is depressed by the performer the rod 20 is raised and the bell crank 80 lever 26 is rotated in a counter clockwise direction as seen in Figure 2. The other arm of the bell crank lever 26 is operatively connected by means of a connecting rod 30 to 85 an arm 31 affixed to the lower end of a rotatable shaft 32.

The shaft 32 is rotatably mounted in spaced journal bearings 33 and 34 which are secured to the fixed casing 10 of the piano. 90 a collar 35 being secured to the shaft 32 to prevent longitudinal movement of the shaft with respect to the bearings. The shaft 32 is provided with a pair of spaced arms 36 and 37 rotating therewith, the arm 36 being 95 adjacent the lower face of the fixed casing 10, while the arm 37 is positioned near the upper face of the fixed casing 10. The outer ends of the arms 36 and 37 are pivotally connected by means of a pair of connecting links 40, 41, respectively, to a pair of connecting rods 42, 43.

An additional or separable casing structure is mounted upon the fixed casing 10 and includes articulated sections such as 48, 49. 105 As shown in Figure 4, each section comprises an upper moulding strip 50 and a lower moulding strip 51, and the contour of these strips corresponds to the configuration of the fixed casing 10, (see Figure 1). The strips 110

50 and 51 are spaced apart in a vertical plane and maintain in position intermediate them a sheet of veneer 52. A narrow strip of moulding 53 is provided to cover the joint 5 between the veneer 52 and the upper moulding 50 and a similar narrow moulding strip 54 is provided for the corresponding lower joint between the veneer 52 and the lower moulding 51. On the inner face of the veneer 10 52 is mounted a strip of sound absorbing material 55 such as felt or the like, and secured to the fixed casing 10 are metal plates 57, 58. At spaced intervals a plurality of long machine screws such as 59, 60, are screwed 15 through the narrow moulding strip, veneer and insulating material into engagement with the metal plates 57, 58, thus securing the separable casing to the fixed casing 10. At the rear of the piano, the two sections 48 20 and 49 are joined as illustrated in Figure 5 of the drawings, and a strip of moulding 61 is provided for concealing this joint, and for holding the sections together.

The separable casing structure may be 25 readily attached or detached from the fixed casing 10 of the piano by means of the machine screws 59, 60 and the two sections 48, 49 of the separable casing may thus be dismounted in a minimum time. When applied 30 to the casing 10 the separable casing serves to suppress the sound produced within the casing 10 through the side walls of the piano.

The casing 10 is also provided with oppositely disposed apertures as at 70, 71. Mounted 35 in the upper aperture 70 is a series of modulating reflectors as at 72, therefor, thus forming controllable closures for the apertures and serving to control the emission of sound. Each reflector is preferably in the 40 form of an elongated flat member pivotally mounted to rotate about its longitudinal axis and is provided on its inner face with a sheet of sound reflecting material 73, such as sheet aluminum or the like. Each reflector is provided 45 with an arm 74, and the arms forming parts of the upper group of reflectors are pivotally connected at their outer ends with the upper connecting rod 43. Similarly there is mounted in the lower aperture 71 a second 50 group of modulating reflectors as at 75, serving to control the emission of sound through the lower apertures. Each reflector 75 is in the form of an elongated flat member rotatable about its longitudinal axis and having 55 on its upper inner face a sheet of sound reflecting material 76 such as sheet aluminum or the like. Each reflector 75 is provided with an operating arm, the outer end of which is pivotally connected with the lower connecting rod 42.

In operation, when the separable casing is applied to the fixed casing as has been hereinbefore described, the manual of the piano may be operated by a musician to cause vibration 60 of the strings by percussion. In order

to produce a desired effect the pedal 17 is depressed to a desired extent. Downward movement of the pedal 17 causes the rod 20 to be moved upwardly so as to rotate the bell crank lever 26 against the tension of the 70 spring 28 in a counter clockwise direction as seen in Figure 2. The connecting link 30 and the connecting rods 42 and 43 are thus moved towards the right and thus the reflectors 72 of the upper group of reflectors are rotated 75 in a clockwise direction and the reflectors 75 of the lower group are rotated in a counter clockwise direction. Assuming that the pedal 17 has been fully depressed, the reflectors are thus adjusted into the fully closed position 80 with the respective apertures closed. The compressional waves are thus reflected back from the metal lined reflectors and the energy of the waves is imparted regeneratively to the 85 strings, so that the vibration of the strings is very greatly sustained. The sound is effectively prevented from emission through the side walls of the casing by means of the insulating characteristics of the separable 90 casing structure described in connection with Figures 4 and 5. By thus insulating the instrument, the proportion of uncontrolled musical sound and of sound leaks is in such ratio to the controlled sound, as to represent a relatively small fraction of the minimum tone emitted from the instrument. Thus improved shading and sensitive control 95 of the musical dynamics are obtained.

When it is desired to emit a portion of the sound produced by the strings the pressure 100 is partly taken off the pedal 17 and the spring 28 causes the pedal and associated parts to be retracted to the extent desired by the musician. The reflectors 72 and 75 are thus caused 105 to be partially opened and an increase in the amount of musical sound emitted from the instrument is obtained. When it is desired to emit a still greater proportion of the sound the pedal 17 is moved upwardly to a still greater degree and the volume of emitted sound is thereby further increased. The reflecting surfaces 73 and 76 greatly improve 110 the control of the tone with respect to the listener.

The invention upon which this application 115 is based is broader than the specific embodiment shown and described for the purpose of illustrating at least one of the ways in which it may be employed. The scope of the invention is therefore to be understood as 120 not being limited by the present specific description. I intend no limitations other than those imposed by the claims.

What is claimed is:

1. In a musical instrument, the combination 125 with means for producing sound by percussion, a fixed casing surrounding said means and having oppositely disposed apertures for the emission of musical sound, and boundary walls intermediate said apertures, 130

of a separable casing arranged to be mounted upon said boundary walls.

2. In a musical instrument, the combination with means for producing sound by percussion, a fixed casing surrounding said means having oppositely disposed apertures, for the emission of musical sound, and boundary walls intermediate said apertures, of a substantially sound proof casing demountably secured to said intermediate walls for suppressing sound transmitted through said intermediate walls.

3. In a musical instrument, the combination with tuned strings for producing musical sound, a fixed casing surrounding said strings and including apertured walls and an imperforate wall, of a separable casing arranged to be mounted upon said imperforate wall.

20 4. In a musical instrument, the combination with means for producing sound by percussion, a fixed casing having oppositely disposed apertures, and an imperforate wall, of a substantially sound proof casing demountably secured to said imperforate walls.

5. In a musical instrument, the combination with a vibratory element, and a percussive action for striking said element to produce damped compressional waves, of a fixed casing surrounding said element, a separable casing structure supported by the fixed casing, said separable casing including two spaced mouldings having the configuration of the fixed casing and a sheet of sound absorbent material supported between said mouldings and in spaced relation with the wall of the fixed casing.

6. In a musical instrument, the combination with a vibratory element, and a percussive action for striking said element to produce damped compressional waves, of a fixed casing surrounding said element, a separable casing structure supported by the fixed casing, said separable casing including two spaced mouldings having the configuration

of the fixed casing, each of the mouldings being formed in sections, means for securing the sections together, and a sheet of sound absorbent material supported between said mouldings and in spaced relation with the 50 wall of the fixed casing.

7. In a musical instrument, the combination with a tuned string, and a hammer for striking said string to produce damped compressional waves, of a fixed casing surrounding said string, and a separable casing structure supported by the fixed casing, said separable casing including articulated mouldings having the configuration of the fixed casing and a sheet of sound absorbent material supported on said mouldings and in spaced relation with the wall of the fixed casing.

8. In a piano, a fixed casing having apertures, a plurality of modulating reflectors 65 positioned in said apertures for variably controlling sound emitted therethrough, a plurality of plates affixed to the fixed casing, a separable casing including a layer of sound insulating material, demountably positioned 70 on the fixed casing, and a plurality of holding screws passing through the insulating material and engaging said plates respectively.

9. In a piano, a fixed casing, a plurality of 75 modulating reflectors for controlling the musical sound emitted, a separable casing structure demountably secured to the fixed casing and comprising a pair of spaced mouldings a sheet of sound insulating material supported between said mouldings and spaced apart from the wall of the fixed casing, and a protective covering for said material supported on the mouldings, and readily removable means for fastening the separable 80 casing structure to the fixed casing.

Signed at New York in the county of New York and State of New York, this twenty-seventh day of November, A. D. 1925.

ALBERT D. TRENOE.
